UNITED STATES PATENT OFFICE.

JAMES BISSLAND AND RICHARD H. WILLIAMS, OF MOUNT VERNON,
NEW YORK.

UMBRELLA AND PARASOL.

SPECIFICATION forming part of Letters Patent No. 237,470, dated February 8, 1881.

Application filed December 23, 1880. (No model.)

To all whom it may concern:

Be it known that we, JAMES BISSLAND and RICHARD H. WILLIAMS, both citizens of the United States, residing at Mount Vernon, 5 county of Westchester, and State of New York, have invented new and useful Improvements in Umbrellas and Parasols, of which the following is a specification.

This invention relates to means for retracting, at or from the lower part of an umbrella-staff, and with the hand in which the umbrella is held, the spring-catch that holds the runner in its upper position on the staff. Prior to our invention this purpose has been accomplished by means of a slide-rod acting directly on the spring-catch—namely, on its shank; but this device is impracticable, because liable to get out of order and not positive in its operation.

Our invention consists in a certain novel combination of parts, hereinafter fully described, and pointed out in the claims, whereby the positive operation or retraction of the spring-catch is insured.

This invention is illustrated in the accompanying drawings, in which—

Figure 1 shows it applied to an umbrella. Fig. 2 is a longitudinal section of the upper part of the umbrella-staff, on a larger scale than in the previous figure. Fig. 3 is a similar section of the lower part of the staff. Fig. 4 is a cross-section thereof on the line xx , Fig. 3.

Similar letters indicate corresponding parts.

The letter A designates the umbrella-staff, 35 terminating in a handle, B, at its lower end, and C the spring-catch serving to hold the runner D in its upper position on the staff.

E designates an elbow-lever pivoted to the staff A on its upper part, and F a similar lever 40 pivoted to the staff on its lower part. These levers E F are connected together by a wire, cord, or chain, G, and the upper lever engages the catch C at its free end, while to the lower lever is connected a thumb-button, H, in such 45 a manner that by pressing upon this button the lower lever is tilted and acts on the upper lever through the wire G or its substitute, to cause the catch to be retracted by its means, whereby the runner D is set free and the umbrella is permitted to close.

The elbow-levers E F are arranged in slots

I J, formed at appropriate points in the staff A, the upper slot containing, also, the catch C; and the staff is made hollow intermediate of these slots, as shown, while the wire G or its substitute extends through this hollow part of the staff. Opposite to the slot J, in the lower part of the staff A, the latter is preferably furnished with a ring, N, the same having a slot, O, for the passage of the shank of the thumb- 60 button H.

It will be readily perceived that the elbow-levers E F, together with their connecting-wire G or its substitute, are an effective means for retracting the catch C, and one which is 65 positive in its operation, while, by the peculiar arrangement of these parts, the good appearance of the staff is preserved.

What we claim as new, and desire to secure by Letters Patent, is—

1. The combination, with an umbrella-staff, and a spring-catch for holding the runner on the upper part thereof, of two elbow-levers pivoted to the staff on its upper and lower parts, respectively, the upper lever engaging 75 the spring-catch, a wire or its substitute connecting the levers with each other, and a thumb-button connected to the lower lever, the whole adapted to operate substantially as described.

2. The combination, with an umbrella-staff, which is constructed with a slot both on its upper and lower parts, and which is hollow intermediate of the slots, and a spring-catch for holding the runner on the upper part of 85 such staff, of two elbow-levers pivoted to the staff within its slots, respectively, the upper lever engaging the spring-catch, a wire or its substitute extending through the hollow portion of the staff and connecting the elbow-levers with each other, and a thumb-button connected to the lower lever, the whole adapted 90 to operate substantially as described.

In testimony whereof we have hereunto set our hands in the presence of two subscribing 95 witnesses.

JAMES BISSLAND.
RICHARD H. WILLIAMS.
